LLC(57) CLAIM

The ornamental design for a cosmetics brush, substantially as shown and described.

DESCRIPTION

FIG. 1 is a perspective view of a cosmetics brush showing my new design;

FIG. 2 is a front elevation view thereof, the rear elevation being a mirror image;

FIG. 3 is a right side elevation view thereof, the left side being a mirror image;

FIG. 4 is a top plan view thereof; and,

FIG. 5 is a bottom plan view thereof.

The broken lines shown in FIG. 1 illustrate portions of the cosmetics brush that form no part of the claimed invention.
